TRANSPARENT ARRANGEMENT

Franz Ovenhausen, Steinheim, Germany

Application September 9, 1931, Serial No. 561,972
In Germany May 15, 1929

9 Claims. (Cl. 240—108)

The present invention relates to a device for the purpose of screening off or attenuating light. This device is particularly adapted for being used as screen in conjunction with illuminating fittings. The screens are made to consist in accordance with the present invention of a spirally shaped wooden veneer leaf, in connection with which the veinage of the wood is made to take a radial course. An arrangement for the production of such veneers has been described in my American Patent 1,807,251. The present invention, however, is not to be limited to screens having been produced in accordance with this patent.

An essential feature of the present invention further consists therein, that the spirally shaped veneer is pared off by means of a tool of such thickness and under such angle, that the screen or the transparent essentially exhibits a veinage fully repeating itself. To the spirally shaped veneer a curved or profiled form is advantageous- 20
ly imparted by the employment of curved cutters. Furthermore, the veneer may be covered with glass or with a similar material on either side.

In the drawing the invention has been shown by way of example,

Fig. 1 showing an arrangement in accordance with the invention in side elevation,

Figs. 2 and 3 representing further examples of performance in accordance with the present invention,

Fig. 4 being a sectional view of a further example of performance, in accordance with the present invention.

In the drawing *a* indicates a spirally shaped veneer exhibiting a veinage essentially fully recurring. The parts *a* have substantially the shape of a truncated cone. In Fig. 1 the point of the cone has been replaced by the stud *c* being connected with the part *a* in a suitable manner, e. g. by glueing or by means of a screw connection. The stud *c* may be made to serve for the reception of a mount for an electric globe. In accordance with Fig. 1 the part *a* merely possesses one joint *g*. If necessary, also several joints may be provided at the part *a*. This joint, however, takes a wave-line course, preferably such a course, which yields a dove-tailed joint.

The example of performance in accordance with Fig. 2 shows an upper part *a* and a lower part *b*. The parts *a* and *b* are connected with each other in a suitable manner. In this example of performance the point of the part *b* has been replaced by a stud *c*. In contradistinction to the part *a* the part *b* is made to consist of a hollow cut spirally shaped veneer.

Fig. 3 shows a spherical illuminating fitting. The sphere has been composed of separate ve-

neer leaves *d*, showing each for themselves a fully recurring veinage. *f* are ledges being provided to hold the separate veneer leaves *d* together. The veneer leaves may also suitably be employed as transparents for illuminated advertising sign-boards, transparent table-tops, illuminated floorings and the like.

Fig. 4 represents a sectional view of a table-top equipped in accordance with the invention. *h* indicates glass plates in between which a veneer leaf *i* has been placed. This veneer leaf corresponds in plan view to the intermediate veneer leaves *d* in accordance with Fig. 3. *k* is an electric globe situated below the table-top. In conjunction with a suitable thickness of the glass plate this arrangement may also be employed as flooring. Below the joint of the wooden veneer leaf a thin veneer or a strip of paper may suitably be placed and glued to the wooden veneer.

I claim:

1. In a casing a wall, the casing adapted for the reception of an illuminating fitting, the wall consisting of a veneer leaf with a veinage essentially taking a radial course, said leaf consisting of an integral piece of wood.

2. In a casing in accordance with claim 1, said wooden veneer leaf being designed as a hollow cone.

3. In a casing a wall in accordance with claim 1, said wooden veneer leaf being designed as hollow cone with curved generatrix.

4. In a casing in accordance with claim 1, on the outside of the wooden veneer leaf a transparent disk and fastening means interposed between said disk and the wooden veneer leaf.

5. In a casing in accordance with claim 1, said wooden veneer leaf being placed between two transparent disks.

6. In a casing in accordance with claim 1, said wooden veneer leaf being interposed between two transparent disks and packings between the edges of the disks.

7. In a casing in accordance with claim 1, said joint edges having the shape of a wave line.

8. In a casing in accordance with claim 1, said joint edges being designed as serpentine line in such a manner, that the tenons thus formed are adapted to grip each other in dove-tail or swallow-tail fashion.

9. In a casing a wall, the casing adapted for the reception of an illuminating fitting, the wall being designed as hollow rotary body and containing veneer leaf with a veinage taking a course essentially parallel to generatrix of said body, the joint edges of said veneer leaf being immediately connected with each other.

FRANZ OVENHAUSEN.
